UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,233,562.

Specification of Letters Patent. Patented July 17, 1917.

Application filed February 23, 1915. Serial No. 10,111.

To all whom it may concern:

Be it known that I, FRANK DUTCHER, a citizen of the United States, residing at Versailles, in the county of Allegheny and 5 State of Pennsylvania, have invented certain new and useful Improvements in Railway Signal-Torpedoes, of which the following is a specification, reference being had therein to the accompanying drawing.

10 This invention relates to improvements in railway signal torpedoes, and it pertains to improvements in that type of torpedo which has a body portion of paper and a metal clip or bottom therefor, which is shown in 15 United States patent granted to Charles E. Beckwith, May 30th 1905 and bearing Number 790,879.

The particular improvements of this invention over the said patent are:

20 First: The making of thinner edges at the ends of the torpedo.

Second: The provision of elongated thin portions extending beyond the explosive within the shell, whereby there is provided 25 an elongated thin portion for the wheel of the locomotive to engage in advance of striking the raised explosive portion for the purpose hereinafter set forth.

Third: To remove the turned over metal 30 flanges so far away from the explosive compound that when the explosion occurs no part of the metal clip or bottom is broken or torn away and thrown through the air to cause probable injury to persons.

35 In the accompanying drawings:

Figure 1 is a perspective view of my improved torpedo, showing it in position on the tread of a railway rail.

Fig. 2 is a longitudinal central sectional view of Fig. 1.

Fig. 3 is a longitudinal central sectional view of a modification of the improvement.

Fig. 4 is a detached perspective view of the paper or shell or tube after it is shaped 45 and before the explosive is placed therein and the clip applied thereto, the said view being of a reduced size as compared with the other figures of the drawing.

Referring now to the drawings, 1 is a 50 paper tube or shell, which is first shaped as shown in Fig. 4. After being so shaped a tablet explosive is pushed endwise therein to the center of the shell or tube. Then a suitable waterproof cement is placed within 55 the elongated flattened ends 3 of the shell,

and the walls of the elongated portions flattened down tight, as shown in Figs. 1, 2 and 3, and held in that position until the cement has become set. To facilitate the manufacture there will be provided a suitable slide- 60 way, not here shown, through which the torpedoes will be forced in succession, and held a sufficient length of time to permit the setting of the cement.

This shell with the explosive therein and 65 in the shape shown in Figs. 1 and 2, is then placed on a metal clip 4. This metal clip 4 has at each end flanges 5, which will stand upward at right angles at the time the shell is placed thereon. The shells with the clip 70 so placed are then put in a suitable press, not shown, and the flanges 5 are clamped down tight on the ends of the shell, as shown, and serve to hold them tightly closed. This clip also serves to hold either a lead 75 or spring rail-engaging strap 6, to the torpedo by means of which it is held upon the tread of the track.

In Fig. 3 is shown a slight modification. This modification consists in providing the 80 clip 4' with lugs 4², which pass through openings 4³ in the ends of the paper shell and then turned outward, as shown, and also serve to hold the ends of the paper shell closed and the rail-engaging strap 6 85 to the torpedo. In this modification the clip is not provided with flanges, as shown in Fig. 2.

By reference to the Beckwith patent, herein mentioned, it will be observed that the 90 shell is so shaped that some of the explosive is under the folded ends of the paper tube and practically under the turned over flanges of the metal clip. This torpedo has been in practical service for a good many 95 years and is regarded as a standard torpedo. However, by reason of the construction referred to, it has also been recognized that the torpedo has very blunt ends for the wheel of the locomotive to strike and when 100 the rails are wet and slippery, have been known to pop from under the wheels and be knocked off the track without being exploded. It has also been well-known that always one, and sometimes both, of the 105 turned over metal flanges are blown away and fly through the air and persons have been injured by such flying of the flanges of this torpedo.

By providing the shell with the elongated 110

thin flattened ends, thin leaders are provided for the wheel of the locomotive to grip before the elevated portion of the torpedo is struck which contains the explosive, thus 5 avoiding the "popping" of the torpedo. Furthermore, this arrangement removes the turned over flanges or lugs so far from the explosive that when the explosive bursts the paper, no part of the metal clip is thrown 10 away and thrown flying through the air.

Still another advantage of this construction is that it is found in the manufacture of the Beckwith construction extreme care 15 must be used in placing the torpedo in the press to have it centralized and provision must be made to limit the downward movement of the jaws of the press to prevent the explosion of the torpedo in the press. Even 20 with this care explosions do at times happen and operators have been injured by such explosions. With this construction such explosions will be impossible by the press, for 25 it will only touch the turned over flanges 5, which are so far removed from the explosive that it is impossible to press that part of the shell which contains the explosive.

While I have described the explosive 2 as of the tablet form, yet I desire it to be understood that a loose powder explosive can 30 be used in this improved shell and with the same advantages as when using the tablet form.

When the loose powder is used one 35 end of the shell will be cemented flat and the other end left open, and while open filled with a loose powder and then the cement placed in the inner side of the open end of

the tube and it is then mashed flat. After this the clip will be placed thereon. It will be understood, of course, that in the filling 40 of the torpedo, the open end will be upright so that the loose powder explosive would not get in between the flat ends of the shell.

Having thus described my invention, what I claim and desire to secure by Letters Pat- 45 ent is:

1. A railway signal torpedo comprising a flat elongated clip, an explosive containing case attached thereto and having its bottom wall in contact with the clip throughout its 50 length, an explosive compound within the case, the case having projecting ends beyond the explosive of a greater length than the thickness of the explosive containing part of the case for the purpose described. 55

2. A railway signal torpedo comprising a flat elongated clip, an explosive containing case attached thereto and having its bottom wall in contact with the clip throughout its length, an explosive compound within the 60 case, the case having projecting ends beyond the explosive of a length greater than the thickness of the explosive containing part of the case, the upper wall of the projecting ends of the case flattened down and 65 cemented to the bottom wall whereby they are held against and parallel with the said bottom wall for the purpose described.

In testimony whereof I hereunto affix my signature in the presence of two witnesses. 70

FRANK DUTCHER.
